(57) **CLAIM**

The ornamental design of a hanging tray bird feeder, as shown and described.

DESCRIPTION

FIG. 1 is an isometric view of a hanging tray bird feeder showing my new design;

FIG. 2 is a top plan view thereof;

FIG. 3 is a front view thereof, the rear view being identical;

FIG. 4 is a left side view thereof, the right side view being identical;

FIG. 5 is a bottom plan view thereof;

FIG. 6 is a cross-sectional view thereof, taken along line 6—6 of FIG. 2;

FIG. 7 is an isometric view thereof in a shipping or storage position; and,

FIG. 8 is an isometric view thereof in a use position.

The broken lines shown in FIGS. 7 and 8 are for illustrative purposes only and form no part of the claimed design.

It is understood that the crosshatch pattern depicting a screen in FIGS. 1, 2, 5, 7, and 8 extends continuously across the surface upon which it is shown.
